COMBINATION KNIFE, LIGHTER, AND FLASHLIGHT

Emil S. Polk, Scarsdale, N. Y.

Application February 26, 1954, Serial No. 29,230

Term of patent 14 years

(Cl. D48—24)

To all whom it may concern:

Be it known that I, Emil S. Polk, a citizen of the United States of America, residing at Scarsdale, county of Westchester, State of New York, have invented a new, original, and ornamental Design for a Combination Knife, Lighter, and Flashlight, of which the following is a specification, reference being had to the accompanying drawing, forming part hereof.

I claim:

The ornamental design for a combination knife, lighter, and flashlight, as shown and described.
